UNITED STATES PATENT OFFICE.

FRANK HENNEBÖHLE, OF CHICAGO, ILLINOIS.

COCK.

No. 831,159.

Specification of Letters Patent.

Patented Sept. 18, 1906.

Application filed June 25, 1904. Serial No. 214,204.

To all whom it may concern:

Be it known that I, FRANK HENNEBÖHLE, a citizen of the United States, residing at Chicago, in the county of Cook and State of Illinois, have invented certain new and useful Improvements in Cocks, of which the following is a specification.

One of the objects of this invention is the production of an improved cock especially adapted for use with fluids under heavy pressure.

Another object of the invention is the production of means for causing the movable valve member to be firmly seated by the pressure of the fluid in the valve-casing in order to prevent leakage around said valve member.

A further object is the provision of means for preventing leakage about the operating-stem of the movable valve member.

A further object is the production of a cock in which the valve member is free to move longitudinally in order to prevent sticking of said valve member upon its seat when expanded by heat.

The invention also relates to means for flushing the interior chambers of the valve to remove sediment.

The invention further refers to the various other improvements in valves hereinafter set forth.

In the accompanying drawings, Figure 1 is a longitudinal central section taken through a straightway cock embodying my invention. Fig. 2 is a sectional view through said cock on dotted line 2 2 of Fig. 1. Fig. 3 is a longitudinal central section through a four-way cock, showing this invention applied to such a cock. Fig. 4 is a fragmental vertical central section through the form of cock shown in Fig. 3, taken on dotted line 4 4 of Fig. 3.

In the construction of a cock embodying this invention I provide a casing 1, having a central chamber 2 of truncated conical form. At its upper end the chamber 2 is closed, save for a central opening 3, adapted to receive the operating-stem of the cock, and at its lower end the chamber is provided in its walls with screw-threads 4, adapted to be engaged by corresponding screw-threads upon a closure 5, which closure has an annular flange 6, adapted to make a tight joint with the lower edge of the casing 1. In its outer face the closure 4 has a rectangular socket 7 for receiving a square wrench. (Not shown.) A

stuffing-box 8, formed integral with the casing 1, surrounds the opening 3 in the upper portion of said casing, and this stuffing-box is exteriorly screw-threaded to receive the gland 9. A packing-ring 10, of usual form, is adapted to lie within said gland, and in this instance, as the packing has been omitted and a rubber washer 11 shown in its place, the packing-ring 10 has been reversed. As will be understood, the ring is placed in its normal position when ordinary packing is used in the stuffing-box.

At its opposite sides the casing 1 is provided with an inlet-opening 12 and an outlet-opening 13, screw-threaded for receiving pipe connections and communicating with the central chamber 2 by means of openings 14 and 15, respectively. A duct 16, communicating between the opening 14 and the upper part of the chamber 2, permits fluid to pass above the valve-plug, to be hereinafter described, and a similar duct 17 communicates between said opening 14 and the lower part of the chamber 2.

A taper valve-plug 18 is adapted to lie within the chamber 2, its integral stem 19 extending upwardly through the opening 3. This opening is closed and the passage of fluid through it prevented by a ground joint, which joint is formed by an annular seating-shoulder 20 on the plug 18, adapted to be seated against the upper closed end of the chamber 2, tightly closing the opening 3 and leaving a small space 21 above the plug. The plug 19 is hollow and on opposite sides is provided with the longitudinal flutes or grooves 22 of a sufficient depth to pass through the walls of said plug, forming the opening 23, extending diametrically through the plug. When the plug is in position in the casing 1, it is free to have a slight vertical movement therein. Thus when said plug is held upwardly by the pressure of the fluid within the cock a small space 24 is formed between the lower end of the plug and the upper side of the closure 4. The exposed area of the lower end of the plug being considerably larger than that of the upper end, the pressure fluid entering the space 24 exerts an upward pressure upon said plug somewhat in excess of the downward pressure exerted by said fluid within the space 21, raising said plug, seating it firmly within the chamber 2, and holding the seating-shoulder 20 tightly in contact with the upper wall of said chamber, thus preventing any leakage either through the

100
105
110

opening 13 or the opening 3. While the plug is free to move longitudinally to take up wear upon the plug, the seating-shoulder 20, and their respective seats, said seating-shoulder keeps the plug from being jammed into its seat and sticking by reason of heavy pressure within the valve. As will be seen, the spaces 21 and 24 are at all times in communication with the inlet, thus preventing leakage.

The plug 19 is rotated to open or close the valve in the usual manner. Fluid entering the casing 1 through the inlet-opening 12 passes through the opening 14, the ducts 16 and 17, and the flute 22 into the spaces 21 and 24 above and below said plug. When the cock is open, the flute 22 within the opposite side of said plug leads from the openings 21 and 24 to the discharge-opening 13, thus permitting of a current of fluid through the spaces 21 and 24, tending to clear them of sediment. Should the pressure within the opening 12 be removed and the plug fall by its own weight against the closure 4, said plug will be raised to its normal position, when the pressure within the opening 12 is restored.

In the form of valve shown in Figs. 3 and 4 the casing 25 is provided with a central truncated conical chamber 26 similar to the chamber 2, which chamber 26 has four openings—namely, an inlet-opening 27, an outlet-opening 28, and openings 29 and 30—for connecting the cock with the opposite ends of a pressure-cylinder. (Not shown.) In this form of cock the plug 31, made tapering, as hereinbefore described, is provided with two curved passages 32 and 33, extending therethrough, which passages are arranged to place the opposite ends of the pressure-cylinder in communication with the inlet-opening 27 and the outlet-opening 28 alternately in the operation of the cock. The casing 25 and plug 31 are constructed, as in the cock first described herein, to provide spaces in the casing above and below the plug. A groove 34 in the wall of the chamber 26 places the space beneath the plug 31 in constant communication with the inlet-opening 27, and a similar groove 35 serves to connect the inlet-opening with the space above said plug. The plug is provided with a seating-shoulder at its upper end, as in the two-way valve.

A considerable portion of the plug 31 being cut away by the openings 32 and 33, I have strengthened the walls of said plug by forming therein the integral transverse pin 36.

The rotation of the plug 31 places the opposite ends of the pressure-cylinder alternately in communication with the inlet and the outlet. As in the form of cock first shown, the pressure fluid holds the plug 32 tightly seated within its chamber 26, with its seating-shoulder pressed tightly against the

end wall surrounding the opening through which the valve-stem passes.

It is apparent that many changes may be made in the devices herein shown without a departure from the invention they embody, wherefore I desire not to limit myself to the particular constructions herein illustrated and described.

I claim as my invention—

1. In a cock, in combination, a casing having an inlet, an outlet, and a conical valve-chamber intermediate said inlet and said outlet; and a rotatable conical valve-plug in said chamber, a space being provided in said casing at each end of said plug, and said plug being fluted upon its opposite sides to connect said spaces with said inlet and said outlet.

2. In a cock, in combination, a casing having an inlet, an outlet, and a conical chamber intermediate said inlet and said outlet; and a rotatable valve-plug adapted to connect said inlet and said outlet, which plug is adapted to contact closely with the conical walls of said chamber, said casing having a passage-way therein for leading pressure fluid from said inlet to the rear of said plug; said plug having a passage-way therein for permitting the flow of fluid from the rear of said plug to said outlet.

3. In a cock, in combination, a casing having an inlet, an outlet, and a conical chamber intermediate said inlet and said outlet; a rotatable tapered plug in said chamber adapted to connect said inlet and said outlet, which plug is adapted to contact closely with the conical walls of said chamber; and a seating-shoulder on the smaller end of said plug adapted to contact with one end wall of said chamber and provide a space between said plug and said end wall, said casing having a passage-way therein for connecting said space with said inlet, and said plug having a passage-way therein for connecting said space with the outlet, said casing and plug also having passage-ways therein for introducing pressure fluid between the larger end of said plug and the adjacent end wall of said chamber and for permitting the flow of fluid therefrom.

4. In a cock, in combination, a casing having an inlet, an outlet, and a conical chamber intermediate said inlet and said outlet; a closure for one end of said chamber, the opposite end of said chamber having an opening extending therethrough; a rotatable tapered valve-plug in said chamber adapted to contact closely with the conical walls of said chamber, said plug having an operating-stem formed integral therewith and extending through the opening in the end wall of said chamber; and a seating-shoulder on the smaller end of said plug adapted to contact with one end wall of said chamber and provide a space between said plug and said end

wall, said casing having a passage-way there-in for connecting said space with said inlet, said casing also having a passage-way there-in for introducing pressure fluid between said closure and the adjacent end of said plug, said plug being fluted on one side to connect said spaces with said outlet.

5. In a cock, in combination, a casing hav-ing an inlet, an outlet, and a conical valve-
10 chamber intermediate said inlet and said out-let; and a rotatable conical valve-plug in said chamber, a space being provided at the larger end of said plug arranged to be at all times in communication with the inlet, said space,
15 when the cock is closed, being entirely closed save for said communication.

6. In a cock, in combination, a casing hav-ing an inlet, an outlet, and a conical valve-

chamber intermediate said inlet and said out-let; a rotatable conical tapered plug in said 20 chamber adapted to connect said inlet and said outlet; an operating-stem on the smaller end of said valve-plug arranged to extend through an opening in said casing; and a seating-shoulder on the smaller end of said 25 plug adapted to contact with the end wall of said valve-chamber surrounding said opening to form a ground joint therebetween, a space being provided at the larger end of said valve-plug, which space is at all times in 30 communication with the inlet.
